OUTDOOR MERCURY LAMP LIGHTING FIXTURE

Larry L. Routh, Castro Valley, and James Contratto,
Livermore, Calif. (both of 1251 Doolittle Drive,
San Leandro, Calif. 94577)

Filed June 24, 1968, Ser. No. 12,484

Term of patent 14 years

Int. Cl. D26—03

U.S. Cl. D48—31

FIGURE 1 is a perspective view of an outdoor mercury lamp lighting fixture showing our new design as viewed from one angle;

FIGURE 2 is a view similar to FIGURE 1 but taken from a different angle; and

FIGURE 3 is a bottom perspective view of the fixture. The light bulbs are shown in broken lines in FIGS. 1 and 2 for illustrative purposes only.

We claim:

The ornamental design for an outdoor mercury lamp lighting fixture, substantially as shown and described.
